DESIGN FOR AN ENSEMBLE DRESS

Samuel Dick, Brooklyn, N. Y.

Application December 29, 1936, Serial No. 66,792

Term of patent 7 years

To all whom it may concern:

Be it known that I, Samuel Dick, a citizen of the United States of America, residing in Brooklyn, county of Kings, and State of New York, have invented a new, original, and ornamental Design for an Ensemble Dress, of which the following is a specification, reference being had to the accompanying drawing, forming part thereof, wherein, particularly the gilet portion of the ensemble, the bolero jacket being removed.

The rear portion of the dress is conventional.

The characteristic feature of my design resides in the detachable gilet portion and the reversible bolero in combination with the dress, as shown.

I claim:

The ornamental design for an ensemble dress, substantially as shown, and described.

SAMUEL DICK.
